UNITED STATES PATENT OFFICE

HARRY ROLNICK, OF DALLAS, TEXAS, ASSIGNOR OF FIFTY PER CENT TO BYER-ROLNICK COMPANY, OF DALLAS, TEXAS, A CORPORATION

HAT BRIM

Application filed June 10, 1930. Serial No. 460,264.

This invention relates to hats; and more particularly, to hat brims.

The prime object is to produce a hat with a turned down brim in front which will retain its shape and which will have a welt extending around the rear portion so as to give the appearance of a welted hat when viewed from the rear, and at the same time, will give all the advantages of a hat having a welt 10 extending around the outer periphery of the brim, and yet permit the turning down of the front edge, so as to give the style of a "snap" front.

Heretofore, hats have usually been finished 15 with a raw edge on the brim, or with what is commonly known as a welted brim. Where the brim is welted, which consists in turning the raw edge inward upon itself and securing the same in position, the hat is not adapted 20 to assume the "snap" effect which consists in having the rear portion of the brim turned up and the front portion turned down, whereas where the edge is raw, this effect and style is obtained and usually utilized. If a "snap" 25 brim is sought with the welted brim, not only is the effect rather undesirable, but the welt in front constantly causes the front portion of the brim to turn up. Where the "snap" effect is obtained with the raw edge hat, the 30 rear portion which is turned up has an unfinished appearance and where the head is unusually long, will tend to pull the hat out of shape, since the welt on the outer brim serves to retain the shape of the hat. By 35 having the welt extend from the rear of the brim part way to the front, the reinforcing shape-retaining advantage is effected, and the front portion is free to be turned down to 40 give the "snap" effect.

Other objects will be disclosed in the specification and drawings forming a part of this application.

In the drawings:

45 Figure 1 is a perspective of a hat shaped

to give the "snap" effect with the brim welted at the rear and raw edged in front;

Figure 2 is a bottom plan of a brim blank before the rear portion has been folded upon itself to form the welt. 50

Figure 3 is a section taken on line 3—3 of Figure 1.

Referring to the drawings in which similar parts are designated by like numerals:

Numeral 4 designates a hat having a crown 55 secured to a brim 6 in the usual manner. The brim 6 has a welt 7 formed on its outer edge and extending substantially half-way around the hat and covering more particularly the rear portion of said brim 6. The 60 front portion 9 of the brim has a raw edge 10 and extends substantially from the middle portion of the hat on both sides continuously around the front portion 9.

As actually made, the brim 6 is cut from a 65 piece of felt, a form being used similar to the brim blank shown in Figure 2. The brim blank 11 consists in a central piece of material having the central portion removed to form an oval opening 12 of the desired size 70 and shape. A projection 13 extends around one-half of the brim blank 11. This projection corresponds to the welt 7 to be formed on the hat brim 6, as described.

Such a hat when viewed from the rear 75 gives the appearance of a welted hat and when viewed from the front has the pleasing effect of the "snap" style and yet does not have the unfinished effect given when the brim has a raw edge. Further, the welt 80 serves to retain the hat in shape when the wearer has an unusual shaped head, and further serves to retain the style when the same has once been shaped. Thus, I have a hat that possesses the advantage of the welted 85 brim and the advantages of the raw edge brim, with none of the disadvantages.

Having described my invention, what I claim is:

1. A hat comprising a brim, having a raw 90

edge in front and a welted portion in the rear so that the front portion may be turned down and the rear portion turned up, the welted portion serving to reinforce and retain the shape of the hat.

5 2. A hat comprising a brim having a raw edge formed on the front portion thereof extending substantially to the middle of the hat, a welt formed on the rear portion of the
10 brim and extending to substantially the middle of the hat, the intersection of the raw edge and welted edge forming an axis for the brim upon which the front portion may be turned down and the rear portion turned up.

15 In testimony whereof I affix my signature.
HARRY ROLNICK.
